(57) **CLAIM**

The ornamental design for a razor, as shown and described.

DESCRIPTION

FIG. 1 is a front, bottom perspective view of a razor, showing our new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is an enlarged top plan view thereof;

FIG. 8 is an enlarged bottom plan view thereof;

FIG. 9 is an enlarged view of detail "9" identified in FIG. 1;

FIG. 10 is an enlarged view of detail "10" identified in FIG. 2;

FIG. 11 is an enlarged view of detail "11" identified in FIG. 3; and,

FIG. 12 is an enlarged view of detail "12" identified in FIG. 4.

The dashed broken lines in the figures illustrate portions of the razor that form no part of the claimed design. The dash-dot-dash broken lines in FIGS. 1, 2, 3, 4, 9, 10, 11 and 12 depict the bounds of the enlarged views and form no part of the claimed design.
